UNITED STATES PATENT OFFICE.

JOHN T. DAVIS, OF OAKLAND, CALIFORNIA.

STILL.

988,445.

Specification of Letters Patent. Patented Apr. 4, 1911.

Application filed October 28, 1908, Serial No. 459,915. Renewed December 27, 1910. Serial No. 599,532.

To all whom it may concern:

Be it known that I, JOHN T. DAVIS, a citizen of the United States, residing at Oakland, in the county of Alameda, State of California, have invented new and useful Improvements in Stills, of which the following is a specification.

My invention relates to an apparatus for distillation and its principal object is to provide a device whereby the process of distillation will be continuous, either for whole or partial distillation. I accomplish this by means that are simple, and by mechanical arrangements that are economical of construction and operation.

By my invention I use superheated steam in pipes, or tubes, as a heating means, and by a mechanical means cause the material to be distilled to flow in a thin film down over the heated pipes, or tubes. The distillates so produced are carried to a condenser, or to condensers if fractional distillation is desired, while the residuum flows from the still through an outlet provided at or near the bottom of the apparatus.

For a better understanding of my invention reference is made to the accompanying drawings, which illustrate an apparatus constructed in accordance with my invention, and which form a part of this specification.

In the drawings like numerals refer to like parts.

In the said drawings: Figure 1, is a side elevation with the casing broken away showing the internal arrangement, Fig. 2, is an end elevation with the casing broken away showing the internal arrangement, and Fig. 3, is a sectional detail view of a trough and partition.

The numeral 1 represents a casing with end pieces 2 of iron or any such suitable material; as will be seen a portion of one of the ends 2 is hinged at 2° so that this part may be moved. Within this casing 1 are horizontal tubes, or pipes, 3 arranged one above the other and joined continuously together as shown by the return joints 4. The uppermost and the lowermost of these pipes 3 extend through the casing 1 at suitable points as shown, and through the walls 5 of the heating chamber 6 and into said heating chamber, where they are suitably connected with the pipes 7 which form the heating coil. Provision is made for admitting water into the pipes 7 of the heating coil as shown by the pipe 8 leading from the reservoir 9, and

in which and with suitable space apart are the valves 10 and 11, though any other well known and suitable device could be used. I have assumed that oil be used as a fuel for supplying heat and in the drawings I have shown the fuel oil supply pipe 12 and a means of supplying steam to the oil burner by the pipe 13 and the cock 14, though it will be apparent that any other fuel adapted to any other well known furnace method could be used. A suitable flue 15 is provided leading from the combustion chamber. 13' is an opening through which the air for supporting combustion passes.

Within the casing 1, and near its top, is a V-shaped trough 16, with perforations 17 along its bottom, or the angle of the said trough where its two sides meet. Leading into the trough 16 is the pipe 18 that is connected with the reservoir 19 provided to supply the fluid to be distilled to the still. A suitable valve 21 is provided in this pipe 18. Within the casing 1 and at, or near, its bottom is another trough 22 provided to receive the residuum and carry it to the outlet pipe 23 that is provided with a suitable trap 24. At the upper part of the casing 1 is the outlet pipe 25 provided to carry the distillates to any suitable condenser 26.

For fractional distillates I provide horizontal partitions which are adapted to be inserted in the casing 1 at suitable points as desired. One of these partitions 26 I have shown in place in Fig. 1, and more in detail in Fig. 3. The partition 26 is provided with a U-shaped notch at 26' into which the bend 4 fits so as to permit the withdrawal of the partition. In detail the partition 26 has a V-shaped trough 27 inserted at or near its center with perforations 17 along the angle of the said trough where its two sides meet. These partitions are designed to be inserted horizontally within the casing 1 between any series of the tubes 3 as may be desired with its trough part directly beneath the tube above it. In the upper part of the chamber 28 so formed within the casing 1 by the partition 26, as shown in Fig. 1, I provide an outlet 29 for the distillates produced in that chamber and leading to the condenser 31.

For the purposes of illustrating the operation of my invention, I will suppose that petroleum is to be distilled, though it will be apparent that it can be adapted for use in most, if not all, processes where distillation is carried on.

Assuming that a desired quantity of water has been admitted into the pipes of the heating coil and fires in the furnace have been lighted, it will be seen that the steam or vapor produced will pass to the pipes in the casing 1. Now oil is admitted from the reservoir 19 by means of the pipe 18. The oil will flow into the trough 16 and pass through the perforations in its bottom in a thin film over the heated pipes and longitudinally with the pipes. It will be seen that the oil coming in contact with the pipes will absorb a portion of the heat units produced in said pipes by the heated vapor within. This will reduce the temperature of the vapor within the pipes over which the oil flows and cause a flow of the vapor from the heating coil into the pipes within the casing 1. Thus will be created a continuous passage of the vapor through the series of pipes within the distilling chamber and the heating coil. The oil as it flows through the apertures of the V-shaped trough comes into contact with the upper pipe of the series and gives off some vapor in its passage over it. Then the oil drops to the next pipe and is further reduced. This repetition over the series of pipes makes a complete distillation of all the hydro-carbons that will be given off at a temperature that is desired to be produced and maintained in the apparatus. The products of distillation are carried by means of the outlet pipes provided to condensers, while the residuum escapes by means of the outlet 23.

Should fractional distillations be required other partitions are inserted at suitable points between the pipes of the series thus forming a series of chambers in which are maintained temperatures suitable to the vaporizing points of the various gravities of

the hydro-carbons of the petroleum. The petroleum passes from one chamber to the other through the perforations in the trough-shaped portions of the partitions. The products of the distillations are then carried to condensers by outlets provided from each of the chambers made in the casing 1 by the insertion of the partitions.

I do not limit myself to the precise construction and arrangement herein described and shown in the drawings, as I desire to avail myself of such modification and equivalents as fall properly within the spirit of my invention.

Having thus described my invention, what I claim as new and desire to secure by Letters Patent is:—

A still comprising a casing, a plurality of pipes arranged horizontally one above the other within said casing and continuously connected together, means for supplying heated vapors to said pipes, a V-shaped trough having perforations in its bottom located above the uppermost pipe, means for supplying the fluid to be distilled to said trough, a removable horizontal partition in the casing, below one of the horizontal pipes, a V-shaped trough forming part of said partition, said trough having perforations in its bottom, and the lower edge of said trough being located immediately above the horizontal pipe which is located immediately below said partition while its upper edges extend on each side of the horizontal pipe arranged above said partition.

In testimony whereof I have affixed my signature in the presence of two witnesses.

JOHN T. DAVIS.
